Cheston Lee Eshelman, 621 NE. 30th Terrace,
Miami, Fla. 33137

Continuation-in-part of abandoned design application Ser.
No. 479,883, June 17, 1974. This application May 16,
1975, Ser. No. 578,191

Term of patent 14 years

Int. Cl. D12—16

U.S. Cl. D12—169

Fig. 1

Fig. 2

Fig. 3

FIG. 1 is a front perspective view of a wheel bumper showing my new design;

FIG. 2 is a side elevational view thereof the opposite side being a mirror image of the side shown herein; and

FIG. 3 is a top plan view thereof.

The broken lines in the drawing are for illustration purposes only.

The bottom of the wheel bumper is substantially flat and unornamented, while the rear follows the contour of the front of the vehicle.

This is a continuation-in-part of design application Ser. No. 479,883 filed June 17, 1974 and now abandoned.

I claim:

The ornamental design for a wheel bumper, as shown and described.
